[57] CLAIM

The ornamental design for a one-piece handle, housing and cover for a draw-type latch or lock, as shown and described.

DESCRIPTION

FIG. 1 is a perspective view of a one-piece handle, housing and cover for a draw-type latch or lock embodying our design, with the view showing principally top, front and left exterior portions thereof;

FIG. 2 is a perspective view showing principally bottom, front and right exterior portions together with interior portions thereof;

FIG. 3 is a top plan view thereof;

FIG. 4 is a bottom plan view thereof;

FIG. 5 is a front side elevational view thereof;

FIG. 6 is a rear side elevational view thereof;

FIG. 7 is a left end elevational view thereof; and,

FIG. 8 is a right end elevational view thereof.
